US0D1091327S

(12) **United States Design Patent** (10) Patent No.: **US D1,091,327 S**
(45) Date of Patent: ** Sep. 2, 2025

(54) **BAG**

(71) Applicant: **James P Sim & Co. Limited**, Glasgow (GB)

(72) Inventor: **Luke Cobbett**, Glasgow (GB)

(73) Assignee: **James P Sim & Co. Limited** (GB)

(**) Term: **15 Years**

(21) Appl. No.: **35/519,552**

(22) Filed: **Dec. 8, 2023**

(80) **Hague Agreement Data**

Int. Filing Date: **Dec. 8, 2023**

Int. Reg. No.: **DM/233982**

Int. Reg. Date: **Dec. 8, 2023**

Int. Reg. Pub. Date: **Dec. 29, 2023**

(51) **LOC (15) Cl.** **09-05**
